UNITED STATES PATENT OFFICE.

HENRY A. WISE WOOD, OF NEW YORK N. Y., ASSIGNOR TO WOOD NEWSPAPER MACHINERY CORPORATION, OF NEW YORK, N. Y., A CORPORATION OF VIRGINIA.

ELECTRICALLY-CONTROLLED PLATE CASTING AND TRIMMING MACHINE.

Application filed November 23, 1925, Serial No. 71,014. Renewed February 12, 1929.

This invention relates to the operation and control of the usual sequence of operations in a machine for casting, cooling and trimming stereotype printing plates. The invention is not limited to any particular type of machine but is capable of general use, not only for stereotype casting machines, but for other machines in which a casting is made and then trimmed by the operation of the machine.

This invention is designed to provide for electric control and operation of the opening and closing of the mold, the filling of the mold with molten metal, the delivery of the plates from the mold, and the mechanical trimming of the cast; in the case of a stereotype printing plate, the mechanical trimming consists in sawing off the tail or riser and trimming the other end. These Junior Autoplate machines as actually constructed have required the manipulation of three separate levers for controlling the opening and closing of the mold, the pumping of the metal and the delivery of the plate and sawing off the tail. Two of these levers require considerable manual exertion in order to operate them in these machines. In accordance with this invention the several functions are performed by power, furnished preferably by electric motors, and the sequence of operations is controlled automatically by the electrical apparatus.

The invention also involves independently of the above indicated combination, the electric operation and control of each of said functions by itself.

Other objects and advantages of the invention will appear hereinafter.

Reference is to be had to the accompanying drawings, in which

Fig. 1 is a plan of an ordinary Junior Autoplate casting and tail sawing machine provided with a preferred embodiment of the present invention involving electrical controlling and operating features, and shown with the mold closed;

Fig. 2 is a similar view shown with the mold open;

Fig. 3 is a side view with the mold closed;

Fig. 4 is a similar view with the mold open;

Fig. 5 is a sectional view on the line 5—5 of Fig. 1 showing the pump and its operating and controlling mechanism;

Fig. 6 is a plan of the machine modified to

provide a different type of control of the means for delivering the plates;

Fig. 7 is a sectional view similar to Fig. 5 showing a modification of the method of operating the pump plunger;

Fig. 8 is a diagram of the electric connections for the construction shown in the first five figures;

Fig. 9 is a similar electric wiring diagram showing the operation of the modification illustrated in Fig. 6; and

Fig. 10 is a similar diagram to go with Fig. 7.

In the first five figures, I have shown the invention as applied to a well known casting machine known in the trade as the "Junior Autoplate" in which a core 1 rotates on a vertical axis and a back 2 reciprocates toward and from it so as to close the mold and open it. The means for reciprocating the back involves a shaft 5 provided with toggles 3 and 4. On this shaft is a worm wheel 6 which is operated by a worm 7 on the shaft of the electric motor 8. This motor is supplied by power, as will be seen later, to rotate the shaft through a half revolution to close the mold and then stop it, and it is then rotated through a half revolution in the reverse direction to open the mold and then is stopped and automatically started again to cast another plate.

When the mold, with a matrix therein, is closed, the metal is pumped into it by a pump comprising a pump cylinder 13, piston 14, piston rod 15 and operating lever 16. This operating lever 16 has been operated by hand heretofore or at last some equivalent of it. When this lever is oscillated, it imparts a movement of reciprocation to the piston 14 which, in the form of pump shown, pumps a charge of molten metal into the mold through a spout 17 upon the raising of the piston. This piston in this case is operated by a motor 20 having a worm 19 on its shaft meshing with a segmental worm wheel 21 fixed to a shaft on which the lever is also fixed. This motor is arranged to turn in one direction through an arc limited by the stroke of the piston and the angle of the segmental worm and then back again to raise and lower the piston. Means is provided, as will be shown later, for automatically returning the piston after a charge of metal has been poured. Electric means is provided, so timed that

when enough time has elapsed to allow the metal in the mold to solidify sufficiently for removal, the motor 8 will start automatically to operate to open the mold and the piston 14 5 will move down to its lowermost position ready for the active reciprocation. The limitation of the movement of the piston rod is electrically controlled, as will appear.

The core 1 rotates a half revolution at a 10 time through a third motor 32, bevel gears 31 and driving shaft 30. This driving shaft has a worm 29 operating a worm wheel 28. On top of the core is a horizontally bevelled gear 26 with which meshes a bevel gear 27 on a 15 shaft 33. This shaft extends diametrically across the top of the core and is provided with a clutch 34 slidable thereon and meshing with a clutch section on the worm wheel 28. This motor 32, instead of operating 20 intermittently and alternately in the reverse directions as the motors 8 and 20 do, runs constantly. Accordingly, the worm wheel 28 rotates constantly. When it is desired to 25 rotate the core 1, the shaft 33 is connected with the worm wheel 28 by the clutch 34. This clutch is operated by a lever 35 electrically, as will appear.

The motor 32 rotates the shaft 30 constantly. This shaft, through gears 40, drives an 30 other vertical shaft 38^a which is mounted on a saw-hanger 38 that is pivoted on the shaft 30 to swing about that shaft as a center. On the saw shaft there are rotary cutters or saws 39 which rotate constantly irrespective of the 35 position of the frame 38.

On the worm wheel 6 is a face cam which 40 operates a lever 37 pivotally connected with a rod 37^a which is in turn pivotally connected with the frame 38. The motion of this lever 37 therefore, swings the frame 38 back and forth about its axis 30 to bring it into and out of position for the saw 39 to cut through the plate on the core as it turns around from casting to delivering position. The cutter 45 or saw 39 thus cuts the tail from the plate while the plate is being delivered, and it is brought into action only when the back is moved away from the core. The other saw 39 trims the other end of the plate.

50 Referring now to the wiring diagram (Fig. 81) it will be seen that the back 2 is provided with a projection at the bottom having a switch-bar 12 provided with wedge-shaped ends, and is also provided with a central projection 47. These wedge-shaped ends are of insulating material and open two pairs of contacts 10 and 11 alternately when the back is in either extreme position, allowing them to close at all other times.

60 The wiring diagram does not disclose the wiring for the motor 32 as that is connected up so that by the usual switch it is thrown into operation when the machine is started and continues to operate all the time as long 65 as the machine is running, and in fact even

if the machine is stopped for short intervals this motor ordinarily will be kept in operation. There is nothing automatic in its control.

The mechanism is under the control of a 70 starting button 44 and a stop switch 81 which are located in the circuits as will appear. The machine is started by pressing the starting button and stopped by breaking the main line connection by means of the stop switch 75 81. When the starting button 44 is pressed connection is made so that the current flows from the main line 100 past the contacts 11 which are open and through the contacts 10 which are closed, through the stop switch 80 which is also closed, through a coil 45, and around the line through button 44, to the main line 101. The only effect of this at this time is to energize the coil 45 which closes a switch 46, bringing together four pairs of 85 contacts in the position marked "Forward". This connects one terminal of the motor 8 through a pair of contacts next to the top ones in said switch 46 with the main 100 directly. The central terminal of the motor is 90 connected through the third pair of contacts directly with the main 101, and the third terminal is connected through the top pair of contacts, as shown in the drawings, with the main 102. Therefore, this motor, which is 95 shown in this case as a three-phase motor, is started. Also the main 101 is connected through the bottom pair of terminals of the switch 46 through the coil 45, stop switch 81, contacts 10, with the line 100, thus keeping 100 the coil 45 energized and the switch 46 closed, although the push button 44 is allowed to be opened by usual springs as soon as it has been pushed to start the currents flowing. Now, of course, the pushing of the stop switch 81 105 and then letting it drop back would cut out the coil 45 and allow the switch 46 to open by the usual spring and thus stop the motor 8 but not until it has completed its cycle.

The motor 8 is now in action and it immediately starts the back 2 forward toward the core, allowing the contacts 11 to close. During the forward motion of the back the lug 47 engages the lever 48 and closes a pair of contacts 49 which previously had been open. 110 This lever 48 is kept in neutral position and restored thereto by a pair of springs. The closing of the contact 49 allows the current to flow from the main 101, around the loop over the open contacts 51, to closed contacts 49 and 115 through a coil 50 which acts to close contacts 51 and open contacts 52. Although when the lug 47 passes over and beyond the switch lever 48 that is restored to neutral position and the contacts 49 are opened again, yet the coil 50 remains energized from the main 101. The current passes then directly to the contacts 51 now closed, through the coil 50, to a 120 pair of closed contacts 59, and then directly to the main 100. Now when the back moves 125 130

clear up to casting position the other end of the switch bar 12 opens the contacts 10 which are directly in series with the coil 45 and therefore de-energizes that coil, opens the 5 switch 46 and stops the motor 8. It is to be noticed, however, that when the contacts 10 are opened by the switch bar 12 the pair of contacts 54 will be closed. This results in the connection of the circuit from the main 101, 10 through the contacts 51, contacts 54, coil 55, which closes a switch 56, and back to the main 100 through contacts 59. The coil 55 is in a shunt closed by the contacts 54 and therefore receiving enough of the current to operate the switch as the coil 55 is designed so as to be operated by part of the current in the main line, as by having more convolutions than the coil 50.

The completion of this circuit closing the 20 switch 56 connects the motor 20 to the three-phase circuit in the same manner as described in connection with the motor 8 and the switch 46 and starts this motor. This motor, as stated above, operates the pump piston 14 to rise and pump a charge of molten metal into the mold. It will be noticed that the piston rod 15 is provided with a bar 25 fastened to it which extends in opposite directions and is provided with adjustable insulating plugs 25 57 and 67 at its opposite ends. At the two ends are located limit switches 23 and 24 which the bar is adapted to engage for the purpose of opening the contacts 59 which have been mentioned and a pair of contacts 69 through a 30 pair of levers 58 and 68.

The plug 57 is so adjusted on the bar 25 that when the piston has risen high enough to discharge a complete charge of molten metal into the mold, this plug will engage the lever 40 58 and open the contacts 59. The first result of this is to de-energize both coils 50 and 55 which are in series with this contact. This results in the automatic opening of the switch 56 which stops the motor 20 as will be obvious. 45 But the coil 61 is now energized, as its circuit is completed from the main 101 through this coil, contact 52, contact 69, which is automatically closed when the bar 25 leaves it on the upward stroke, and back to the main 100. 50 This closes the switch 62 which connects up the motor 20 in the reverse direction and causes the motor to move the plunger down. When the adjustable plug 67 engages the lever 68 and opens the contacts 69, the coil 61 is 55 de-energized as will be obvious and the switch 62 opens, causing the motor 20 to come to rest.

The return of the piston after the metal is discharged into the mold is so regulated that when a sufficient interval of time has 60 elapsed to allow the molten metal to solidify and permit the mold to be opened, a lug 22 adjustably secured on the bar 25 or on the piston rod 15 strikes a lever 64 projecting from the timer switch 21. This closes the contact 65 65 momentarily, which results in the excita-

tion of a coil 66, the current flowing from the main 101 directly to the contact 65 and then to the coil 66 around through the contacts 11 to the main 100. This closes the switch 70 and starts up the motor 8 in the reverse direction. This motor operates to draw the back 70 2 away from the core. After the switch 70 operates, the coil 66 remains in circuit, even though the contact 65 is open. This takes place in the same manner as is described in 75 connection with the coil 45. This movement of the back 2 acts through the link 37^a to swing the saw frame into a position adjacent to the core so that, as the plate swings around with the core, the tail will be severed by the 80 constantly rotating saw 39.

As the casting box nears the end of its backward motion, the lug 47 engages the lever 48 and closes contact 71 which connects the main 101 through the contact 71 with solenoid 85 36 and then back through the stop switch and contacts 10 to the main 100.

The operation of the solenoid 36 draws the plunger 72 and with it the lever 35 back so as to pull the cam roll 74 out of the notch in 90 the core clutch cam 76 and this permits the core to rotate to deliver the plate, as will appear later. The back completes its backward motion until the switch bar 12 opens the contact 11, which de-energizes the coil 66, opening the switch 70, and stops the motor 8. When the solenoid 36 operates, it closes the contact 75, which connects the line from the main 101 with the coil 77 which is connected to the main 100 through the contact 10. This 95 closes two pairs of contacts 78 and 79. Now, when the cylinder cam rotates half way around so that the cam roll 74 drops into the notch of the core cam 76, the core clutch 105 34 opens, which brings the core to a standstill. This action takes place, the clutch of course being operated directly by the solenoid and the lever 35, at the same time that the contact 80 is made by the swinging of the lever 35 back into normal position. This in conjunction with contact 78 closes the circuit which 110 energizes the coil 45. Therefore the switch 46 closes and the motor 8 starts up to move the back forward exactly as stated at the beginning of the description of the operation 115 and another cycle of operations is automatically repeated. It will be understood, of course, that this repetition will be kept up automatically as long as desired without further attention but that all the casts during this 120 period are made from the same matrix.

If it is desired to change the matrix, or stop the operation for any reason, the stop switch 81 is pushed to open the circuit through the coil 45. Therefore, even though this happens in the midst of the sequence of operations for manufacturing a plate the apparatus will continue to function until one more plate is made and the tail removed. Then, and only then, will it stop with the casting box open 130

ready for its matrix to be removed and a new one inserted. All these operations take place without the necessity of the operator having to reposition the machine to effect a 5 change of matrix.

Fig. 6 shows a slightly different embodiment of the above invention in that motor 32, instead of running constantly as is the case in the above described construction, is 10 started by means of suitable electrical connections, shown in Fig. 9, only when it is desired to rotate the core, and is stopped when the cylinder has completed its half revolution. This is done by eliminating the clutch 15 34 and substituting the necessary electrical apparatus as shown in Fig. 9 in which the wiring is the same as in Fig. 8 except as indicated.

This operation of the machine is as follows:

As the casting box opens, lug 47 strikes lever 48, making a momentary contact 76. This energizes coil 60 which closes switch 63, causing motor 32 to rotate the core and the 25 core cam. As the core cam rotates, cam roller 74 rides out of the notch and contact 53 is closed, keeping coil 60 energized after contact 76 is broken. When the core has made one-half revolution, the cam roller drops in 30 the notch on the core cam, thus opening contact 53 through lever 35. This deenergizes coil 60, allowing switch 63 to open, which stops motor 32 and the rotation of the core. The operations are then carried on as described in the first five figures.

Fig. 7 is another embodiment of the method of operating the pump. While in the arrangement described above, the pump is controlled by a motor which reciprocates the 40 piston rod through suitable gearing, in Fig. 7, I show a pump operated by solenoid 43 which pulls the piston upwardly, the reversal of the piston being accomplished by gravity. While the method of controlling the solenoid 45 is similar to that used for controlling motor 20, it is specifically controlled as shown in Fig. 10.

The method of operation is herewith described:

50 As the casting box begins to close, lug 47 strikes lever 48, making contact 49 momentarily. This energizes coil 50 which closes contact 51. Coil 50 remains energized after contact 49 is broken.

55 When the mold fully closes, contact 54 is made energizing solenoid 43. This causes plunger 83, which is secured to piston rod 15, to move upward thus pumping metal into the mold. When sufficient metal has been 60 pumped, plug 84, which is adjustably secured to piston rod 15, strikes lever 85, opening contact 86. This deenergizes both solenoid 43 and coil 50 allowing gravity to pull the pump plunger down. The remaining op-

erations are the same as those shown in the 65 first five figures.

It will be seen therefore that by this invention all laborious manual exertions on the part of the operator are entirely eliminated in this class of machines and that I have 70 substituted therefor merely a push button for starting the machine and a stop button for stopping it. I have provided for the automatic operation of the machine to complete a cast after the stop button is pushed to disconnect the motors from the power after the cycle of operations is finished. This not only 75 avoids manual exertion on the part of the operator but frees him from constant attendance on the machine so that one operator 80 might be able to run more than one machine. Other advantages are secured as I have stated above.

Although I have illustrated and described only three forms of the invention, I am 85 aware of the fact that the electrical connections can be changed by any one skilled in the art without departing from the scope of the invention as expressed in the claims.

Therefore I do not wish to be limited in 90 these respects, but what I do claim is:—

1. In a stereotype printing plate casting machine, the combination with a rotatable core and a reciprocable back together constituting the mold, of a shaft, means operated 95 by the shaft for moving the back to and from the core, a motor connected with the shaft, means for connecting the motor with a source of power to operate to close the mold, automatically actuated means for disconnecting the motor from the source of power when the back has reached its innermost position adjacent the core, means for automatically connecting said motor with the source of power in reverse after a casting has been 100 chilled in the mold to cause the motor to turn in the opposite direction and swing said means back to move the back to its original position, automatic means operated by the movement of the back for disconnecting the motor when the back reaches its extreme open position, and means for automatically starting the motor again to cause another complete reciprocation of the back.

2. The combination with a stereotype plate casting machine, comprising a core and a reciprocable back, of a motor, means operated by the motor for moving the back to and from the core, an electric circuit comprising a starting button and a coil connected to be energized by the pushing of the starting button, a switch in position to be closed by the coil, conductors adapted to be connected with a source of power and with said motor by said switch to cause the motor to rotate and move the back toward the core, a lug movable with the back, a contact operated by said lug, a conductor adapted to be 115 120 125

closed by said contact, a second coil connected with said conductor and adapted to be rendered operative when that contact is closed, a switch operated by the second coil and arranged to keep the coil energized as the back moves forward, and means carried by the back for opening the circuit to the first mentioned coil and allowing the switch to open when the back moves into closed or casting position against the core, thereby causing the motor to stop.

3. In a casting machine, the combination with a core and a reciprocable back, together constituting the mold, of a shaft, arms on the shaft, links operated by said arms for moving the back to and from the core, means for operating the shaft, means for connecting the first named means with a source of power to operate to close the mold, automatic means for connecting the first named means with the source of power in reverse after a casting has been chilled in the mold to swing the arms back and move the back away from the core, means for disconnecting the first named means when the back reaches its extreme open position, automatic means for starting the first named means again to cause another complete reciprocation of the back, and a stop switch for stopping the continued operation of the back.

4. In a casting machine, the combination with a core and a reciprocable back together constituting the mold, of a shaft, means operated by said shaft for moving the back to and from the core by a half revolution of the shaft, manually controlled means for connecting the shaft with a source of power to close the mold, automatically actuated means for disconnecting the shaft from the source of power when the shaft is rotated half a revolution to close the mold, and automatic means for connecting said shaft with the source of power in reverse after a casting has been chilled in the mold to cause the shaft to turn in the opposite direction and move the back to its original position.

5. In a casting machine, the combination with a core and a concave back together constituting the mold, of a shaft, means operated by said shaft for moving the back to and from the core by a part revolution of the shaft, manually controlled means for connecting the shaft with a source of power to close the mold, and automatically actuated means controlled by the back for disconnecting the shaft from the source of power when the shaft is rotated far enough around to close the mold.

6. In a machine for casting, the combination with a rotatable core and a reciprocable back, of means for moving the back to and from the core, means for connecting the first named means with a source of energy, means operated by motion of the back for disconnecting the first named means from said

source when the back engages the core, and automatically actuated means for thereafter connecting the first named means again with a source of power in the reverse to move the back away from the core.

7. In a machine for casting, the combination with a core, and a concave back together constituting a mold, of means for moving the back to and from the core, means for connecting the first named means with a source of energy, and means operated by motion of the back for disconnecting the first named means from said source when the back reaches its innermost position adjacent the core.

8. In a casting machine, the combination with a two-part mold, one part being reciprocable, of a motor and means for connecting and disconnecting the mold with the motor to close the mold, automatically open the mold after an interval for the setting of the casting, and restart the cycle of operations automatically.

9. In a machine for casting stereotype printing plates, the combination with a core and a concave back, of means for reciprocating the back to and from the core, means operated by motion of the back for stopping the back when the mold completely closes, a pump for supplying the mold with metal, means for operating the pump, and means for automatically stopping the operation of the pump when the back reaches its innermost position adjacent the core.

10. In a stereotype plate casting machine, the combination with a core and a reciprocable back constituting the mold, of a motor, electrically controlled means for operating said motor, means connected with the motor for reciprocating the back to and from the core, a second motor, a pump having a piston connected to be operated by the second motor for introducing metal into the mold, means carried by the back for breaking a contact when the back closes against the core and stopping the first motor, means carried by the back for making a contact when the back closes against the core for closing a circuit to connect the second motor with a source of power, means connected with the piston for reversing the connection of the second motor with the source of power when the piston moves to a position to fill the mold to bring the piston back to its inactive position, and means for then stopping the second motor and piston.

11. In a stereotype plate casting machine, the combination of a core and a reciprocable back constituting the mold, with a motor, electrically controlled means for operating said motor, means connected with the motor for reciprocating the back to and from the core, a second motor, a pump having a piston connected to be operated by the second motor for introducing metal into the mold, means

125
130

carried by the back for breaking a contact when the back closes against the core and stopping the first motor, means carried by the back for making a contact when the back 5 closes against the core to connect the second motor with a source of power, and means connected with the piston for reversing the connection of the second motor with the source of power when the piston moves to a position to 10 fill the mold with metal, the means for controlling the second motor comprising two switches each having a coil for operating it, said coils being in said circuits, one of said coils being connected to be deenergized by the 15 movement of the piston to its extreme position for filling the mold, thereby causing its switch to open and stop the second motor, the other coil being connected to be energized at the same time for closing its switch to reverse 20 the motor.

12. In a casting machine, the combination of a core and a reciprocable back constituting the mold, with means for reciprocating the back to and from the core, a motor, a 25 pump having a piston connected to be operated by the motor for introducing metal into the mold, means carried by the back for making a contact when the back closes against the core to connect the motor with a source of 30 power, and means connected with the piston for reversing the connection of the motor with the source of power when the piston moves to a position to fill the mold with metal, the means for controlling the motor comprising 35 two switches each having a coil for operating it, said coils being in said circuits, one of said coils being connected to be deenergized by the movement of the piston to its extreme position for filling the mold, thereby causing its switch to open and stop the motor, the other coil being connected to be energized at 40 the same time for closing its switch and reverse the motor.

13. In a casting machine, the combination 45 with a core and a reciprocable back constituting the mold, of means for reciprocating the back to and from the core, a motor, a pump having a piston connected to be operated by the motor for introducing metal into the 50 mold, means carried by the back for making a contact when the back closes against the core for closing a circuit to connect the motor with a source of power, means connected with the piston for reversing the connection of the 55 motor with the source of power when the piston moves to a position to fill the mold to bring the piston back to its inactive position, means for stopping the motor and piston, and means for automatically connecting the 60 motor to repeat the cycle of operation.

14. In a casting machine, the combination 65 with a mold, of means for closing and opening the mold, said mold comprising a core and a back movable to and from the core, a pump having a piston for supplying the mold with

metal, a motor for operating said piston, and means for automatically connecting the motor with a source of power when the back reaches its inner-most position adjacent the core. 70

15. In a casting machine, the combination with a mold, of a pump having a piston for supplying the mold with metal, a motor for operating said piston, means whereby when the mold closes the motor will be connected automatically with a source of power to raise the piston and fill the mold, means for automatically stopping and reversing the motor to lower the piston, and means actuated by the lowering of the piston for controlling the 80 automatic opening of the mold and delivery of the casting from the mold. 75

16. In a machine for casting, the combination with a core, a concave back, a pump for supplying the mold with metal, means whereby when the mold closes connections will be made to operate the piston to fill the mold, of means for connecting the core to cause it to rotate and deliver the cast plate, and means controlled by the pump for operating the second means. 85

17. In a machine for casting, the combination with a core, a concave back, a pump for supplying the mold with metal, a motor for operating the piston of the pump, means whereby when the mold closes the motor will be connected with a source of power to raise the piston and fill the mold, of a constantly rotating shaft, a clutch for connecting the shaft with the core to rotate the core and deliver the cast plate, and means controlled by the pump piston for operating the clutch. 95 100

18. In a machine for casting, the combination with a core, a concave back, a pump for supplying the mold with metal, means for operating the piston of the pump, means whereby when the mold closes the piston will be connected with a source of power to raise the piston and fill the mold, of a constantly rotating shaft, a clutch for connecting the 110 shaft with the core to rotate the core and deliver the cast plate, means operated by the pump piston for operating the clutch to start the core to rotating, and means for stopping the rotation of the core with the plate thereon 115 at the end of a half revolution to deliver the plate. 110

19. In a machine for casting, the combination with a core, a concave back, means for moving the back, a pump for supplying the mold with metal, means for operating the piston of the pump, and means whereby when the mold closes the piston will be connected with a source of power to move the piston and fill the mold, of a constantly rotating shaft, a clutch for connecting the shaft with the core to rotate the core and deliver the cast plate, means operated by the pump piston for operating the clutch to start the core to rotating, means for stopping the rotation of the 120 125 130

core with the plate thereon at the end of a half revolution to deliver the plate, a constantly rotating saw shaft, a saw thereon, and means operated by the back moving means for moving the saw shaft into position for the saw to cut the tail from the plate as the core commences to rotate.

20. In a machine for casting stereotype printing plates, the combination with a rotatable core, and a reciprocable back, of means for moving the back to and from the core, a saw shaft having a saw thereon, a pump for filling the mold, means controlled by the pump for rotating the core to deliver a cast plate, and means operated by motion of the back for moving the saw into a position to saw off the tail as the casting is delivered.

21. In a machine for casting stereotype printing plates, the combination with a rotatable core, a reciprocable back, a pump, and a motor, of means operated by the motor for moving the pump piston to fill the mold, means for connecting the motor with a source of electrical energy, means controlled by the pump for starting the core to rotate to deliver a cast plate, a movable frame, a saw shaft on said frame, means operated by motion of the back for moving said frame into position for the saw to remove the tail of the plate as the core rotates, automatically actuated means for thereafter stopping the core, and means for disconnecting said motor from the source of power and then connecting it in the reverse.

35. 22. In a casting machine, the combination with a rotatable core and a reciprocable back together constituting the mold, of a shaft, a movable frame, a shaft with a cutter thereon mounted on said frame, a cam on the first shaft having a cam guide extending part way around the shaft, means controlled by said cam for moving the frame to and from the core by a part revolution of the shaft, whereby the cutter will engage the cast plate on the core, and automatic means for starting the core to rotate when the cam moves the frame and cutter into position to cut the tail from the plate.

23. In a stereotype plate casting machine, the combination of a core and a reciprocable back constituting the mold, with a motor, electrically controlled means for operating said motor, means connected with the motor for reciprocating the back to and from the core, a pivoted saw frame, a second motor, a pump having a piston connected to be operated by the second motor for introducing metal into the mold, means carried by the back for breaking an electrical contact in the first motor circuit when the back closes and stopping the first motor, means carried by the back for making a contact, when the back closes against the core, to connect the second motor with a source of power, means connected with the piston for connecting the sec-

ond motor with a source of power when the piston moves to a position to fill the mold with metal to cause the motor to reverse and bring the piston back to its inactive position, means controlled by said piston for automatically connecting the core with a source of power to rotate it and deliver the cast plate thereon, and means operated by the first named motor for swinging said saw frame toward the core into position for the tail to be severed as the core turns.

24. In a casting machine, the combination of a core and a reciprocable back constituting the mold, means for reciprocating the back to and from the core, a pivoted saw frame, a pump having a piston for introducing metal into the mold, means carried by the back for stopping the back when the back closes against the core, means carried by the back for operating the piston when the back closes against the core, means for reversing the piston when the piston moves to a position to fill the mold with metal and bring the piston back to its inactive position, means controlled by said piston for automatically connecting the core with a source of power to rotate it and deliver the cast plate thereon, and means operated by the back reciprocating means for swinging said saw frame toward the core into position for the tail to be severed as the core turns.

25. In a machine for casting stereotype printing plates, the combination with a rotatable core and a reciprocable back constituting a mold, of a pump having a piston for introducing metal into the mold, a motor connected with the back for reciprocating it, a motor connected with the core for turning it, a motor connected with the pump for reciprocating the piston, and electrically operated connections for automatically operating said motors in a predetermined order and stopping them to close the mold, introduce a charge of metal therein, open the mold, and turn the core a half a revolution to deliver the plate.

26. In a machine for casting stereotype printing plates, the combination with a core and a concave back, together constituting a mold, of a motor, means operated by said motor for moving the back to and from the core, means actuated by the back moving means for connecting the motor with a source of electrical energy and for automatically disconnecting the motor from said source when the back reaches its innermost position adjacent the core.

27. In a machine for casting stereotype printing plates, the combination with a core and a concave back, together constituting a mold, of a motor, means operated by said motor for moving the back to and from the core, means actuated by the back moving means for connecting the motor with a source of electrical energy and for automatically

disconnecting the motor from said source when the back reaches its innermost position adjacent the core, and means for thereafter automatically connecting said motor again 5 with a source of power to cause the motor to reverse or turn in the opposite direction and move the back away from the core.

28. In a stereotype plate casting machine, the combination with a core, a back movable 10 toward and from said core, the core and back together constituting a mold, of a motor, means operated by the motor for moving the back to and from the core, electrically controlled means for stopping the motor when 15 the back reaches its innermost position adjacent the core, electrically controlled means for reversing the motor so timed as to allow the casting to set, means for stopping the motor when the back reaches the farthestmost 20 position from the core, and means for restarting said cycle of operations.

29. In a stereotype printing plate casting of power to operate to close the mold, automobile, the combination with a rotatable 25 the core, a motor connected with the shaft, means for connecting the motor with a source matically actuated means for disconnecting core and a reciprocable back together consti- by the shaft for moving the back to and from 30 tuting the mold, of a shaft, means operated

the motor from the source of power when the back has reached its innermost position adjacent the core, and means for automatically connecting said motor with the source of power in reverse after a casting has been 35 chilled in the mold to cause the motor to turn in the opposite direction and swing said means back to move the back to its original position.

30. The combination with a stereotype 40 plate casting machine, comprising a core and a reciprocable back, of a motor, means operated by the motor for moving the back to and from the core, an electric circuit, a lug movable with the back, a contact operated by said 45 lug, a conductor adapted to be closed by said contact, a second coil connected with said conductor and adapted to be rendered operative when that contact is closed, a switch operated by the second coil and arranged to keep the 50 coil energized as the back moves forward, and means carried by the back for opening the circuit to the first mentioned coil and allowing the switch to open when the back moves into closed or casting position against 55 the core, thereby causing the motor to stop.

In testimony whereof I have hereunto affixed my signature.

HENRY A. WISE WOOD.
